UNITED STATES PATENT OFFICE.

EDWARD J. HARRINGTON, OF NORTH GIRARD, PENNSYLVANIA.

INTERNAL-COMBUSTION MOTOR.

1,102,912.

Specification of Letters Patent.

Patented July 7, 1914.

Application filed September 15, 1913. Serial No. 789,799.

To all whom it may concern:

Be it known that I, EDWARD J. HARRINGTON, a citizen of the United States, residing at North Girard, in the county of Erie and State of Pennsylvania, have invented certain new and useful Improvements in Internal-Combustion Motors; and I do hereby declare the following to be a full, clear, and exact description of the invention, such as will enable others skilled in the art to which it appertains to make and use the same, reference being had to the accompanying drawings, and to the letters of reference marked thereon, forming part of this specification.

My invention relates to internal combustion motors, and particularly to that type thereof which are adapted to use oil from which the explosive gas is generated.

The object of my invention is the production of an internal combustion motor which shall be so constructed that the fuel oil will be brought into contact with a heated surface in proper quantities, and in combination with a sufficient amount of air to produce an explosive gas, which shall then be forced into the piston cylinder; to provide means whereby the residuum of a preceding exposition will be expelled therefrom by pure air, previous to the admission thereof into of the explosive gas; to provide suitable means for suspending the reciprocating members of the motor so as to avoid unnecessary friction and wear.

These and other features of my invention will appear hereinafter in the specification and claims, and are illustrated in the accompanying drawings in which:

Figure 1, is a plan view of an internal combustion motor embodying my invention. Fig. 2, is a vertical central section thereof. Fig. 3, is a transverse section thereof on the line X—X in Fig. 2, portions of the motor being broken away, looking in the direction of the arrow. Fig. 4, is a longitudinal vertical section of a portion of the cylinder thereof. Fig. 5 is a side elevation of a portion of the cylinder thereof.

In these drawings, A, indicates the base frame of, and A', indicates the cylinder of a combustion motor embodying my invention. B, and B', indicate the pistons thereof, the said pistons B and B', each being substantially one third of the length of said cylinder A'. I have shown the cylinder A', as constructed in three sections, but I find it will be preferable to form it in one piece,

and herein I therefore refer to it with a single reference character.

The cylinder A', is provided with exhaust ports a, and an annular exhaust chamber A², with which the exhaust pipe A³, communicates. These exhaust ports are so located with reference to the length of the cylinder A', as to be uncovered by the backward movement of the piston B', as shown in Fig. 2. Surrounding the exhaust chamber A², I provide an annular fuel chamber A⁴, with which the pipe C, communicates, said pipe C, extending from one end of the cylinder A', to said fuel chamber A⁴, and being provided with a check valve C'. The cylinder A', is also provided with fuel intake ports a', and with air intake ports a², which latter are nearer to the middle portion of the cylinder A', than the fuel intake ports a'. The fuel intake ports a', communicate with the annular fuel chamber A⁴, by means of a longitudinal chamber A⁵, (see Fig. 4) in which chamber A⁵, I provide a throttle valve D, by means whereof the supply of fuel from the fuel chamber A⁴, may be cut off when desired. From one end of the cylinder A', a pipe C², leads to the air intake ports a². It is to be understood that the semi-annular chambers E and E', which communicate with the fuel intake ports a', and air intake ports a², are divided by a wall e, (shown in broken lines in Fig. 2). The cylinder A', is provided with slots F, (see Fig. 5) on opposite sides thereof through which trunnion pins G, pass, which pins are secured in each of the pistons B, and B', said slots F, being of such length as to be uncovered by the forward movement of the pistons B and B', so as to permit air to enter the cylinder A', behind each piston. Above the middle portion of the cylinder A', I mount in suitable bearings, a crank-shaft H, having four cranks H', therein. To the trunnion pins G, I pivot bifurcated levers J. For supporting the upper ends of these levers J, I provide an upright support K, which may be secured upon the frame of the motor at any convenient point. To this support K, I pivot arms L, to which the upper ends of the levers J, are pivoted. I also preferably provide a spring L', adapted to press upwardly on the arms L, with sufficient force to counter-balance the weight of the arms L, levers J, and pistons.

To the levers J, and cranks H', pitmen M,

are pivoted by means of pivot rods N. A spark-plug P, is provided in the wall of the cylinder A', and fuel oil is supplied to the pipe C, by means of a pipe Q. A water supply mechanism R, is also provided by means of which water may be supplied to the air intake ports α^2 , to supply the requisite moisture.

S, indicates a water jacket chamber 10 around the middle portion of the cylinder A', and T, indicates a fly-wheel on the shaft H.

In operation, when it is desired to start this motor, a sufficient quantity of gasoline 15 may be introduced into the pipe C, through the cover of the check-valve C', and fuel-oil supplied thereto through the pipe Q. The fly-wheel T, is then revolved manually, which will cause the pistons B, and B', to 20 move toward each other, so that when the slots F, are uncovered or opened by the pistons B and B', air rushes into the cylinder behind said pistons, and when the pistons travel backward toward the ends of the cylinder A', the air behind them is compressed 25 thereby, and when the air intake ports α^2 , are uncovered, air rushes through the pipe C², and ports α^2 , into the cylinder A', driving any residue from the last preceding explosion 30 out through the exhaust ports α , and the uncovering of the fuel ports α' , by the piston B, permits explosive vapor from the gasoline to be forced into said cylinder by the compression of air behind the piston B', 35 which is communicated thereto through the pipe C, and chambers A⁴ A⁵ and E. As soon as the wall of the exhaust chamber A², becomes heated from the exhaust of the engine, the fuel oil introduced through the pipe 40 C, and carried by the air into the annular fuel chamber A², volatilizes in said chamber and the resulting explosive vapor passes to the fuel intake ports α' , and thence into the cylinder, at each uncovering of said ports. It 45 will therefore be obvious that in my improved motor, the products of combustion are first blown out of the cylinder through the exhaust ports α , by the uncovering of the air intake ports α^2 , and are followed by the 50 explosive mixture, and that this mixture is compressed by the pistons during their movements toward each other prior to being fired by the spark.

Having thus fully shown and described 55 my invention so as to enable others to construct and operate the same, what I claim as new and desire to secure by Letters-Patent, is:—

1. In an internal combustion motor, a 60 cylinder having exhaust ports, and air and fuel intake ports, heads on the ends of said cylinder, pistons in said cylinder adapted to cover and uncover said ports during their reciprocations therein, and to compress air 65 between them and the heads of said cylinder,

a fuel chamber adjacent to said exhaust ports and communicating with said fuel intake ports, tubular communication between one end of said cylinder and said fuel chamber, means to introduce fuel oil thereinto, 70 and tubular connections from the other end of said cylinder and said air intake ports, substantially as set forth.

2. The combination in an internal combustion motor, of a cylinder having exhaust 75 ports and fuel intake ports, heads on the ends of said cylinder, pistons in said cylinder adapted to cover and uncover said ports during their reciprocations and to compress air between one of said pistons and one of the heads of said cylinder, a fuel chamber adjacent to said exhaust ports and communicating with said fuel intake ports, a tubular connection between one end of said cylinder and said fuel chamber adapted to 80 conduct air from said cylinder to said fuel chamber, a check valve therein, means to introduce fuel oil into said fuel chamber, a crank-shaft, a fly-wheel thereon, lever mechanism connected to said pistons, and pitmen pivoted to the cranks in said crank-shaft, and to said lever mechanism, substantially as 85 set forth.

3. The combination in an internal combustion motor, of a cylinder having exhaust 95 ports, fuel intake and air intake ports, in the intermediate portion thereof, and slots through the walls of the end portions thereof, said air intake ports being located nearer the middle of the cylinder than said fuel intake ports, pistons in said cylinder adapted to cover and uncover said ports during their reciprocations, trunnion-pins secured in said pistons and extending outwardly through said slots in the walls of said cylinder, lever 100 mechanism pivoted to said trunnion pins, means to support said lever mechanism, a crank-shaft, pitmen pivoted to said lever mechanism and the cranks in said crank-shaft, a fly-wheel on said shaft, a fuel chamber adjacent to said exhaust ports and communicating with said fuel intake ports, a tubular connection between one end of said cylinder and said fuel chamber, a check-valve therein, means to introduce fuel oil 105 into said chamber, and a tubular connection between the other end of said cylinder and said air intake ports, substantially as set forth.

4. The combination in an internal combustion motor, of a cylinder having exhaust ports, fuel intake and air intake ports in the intermediate portion thereof, and slots through the walls of the end portions thereof, said air intake ports being located nearer the middle of the cylinder than said fuel intake ports, an annular exhaust-chamber around said cylinder inclosing said exhaust ports, an annular fuel chamber around said exhaust chamber and communicating with 110

5 said fuel intake ports, a tubular connection between one end of said cylinder and said fuel chamber, a check-valve therein, means to introduce fuel oil into said fuel chamber,
10 a tubular connection between the other end of said cylinder and said air intake ports, pistons in said cylinder adapted to cover and uncover said ports during their reciprocations, trunnion-pins secured in said pistons
15 and extending outwardly through said slots, levers pivoted to said trunnion-pins, means to support the opposite ends of said levers, a crank-shaft, a fly-wheel thereon, pitmen pivoted to the cranks in said shaft and to
20 said levers, and means to counter-balance the weight of said levers, pitmen and pistons, substantially as set forth.

25 5. The combination in an internal combustion motor, of a cylinder having exhaust ports, and air and fuel intake ports in the intermediate portions and longitudinal slots in the end portions thereof, a fuel chamber adjacent to said exhaust ports, a tubular connection between said fuel chamber and
25 said fuel intake ports, a regulating valve in said connection whereby the volume of fuel

30 mixture flowing to said intake ports may be regulated, a tubular connection between one end of said cylinder and said fuel chamber, a fuel oil supply pipe leading into said
35 tubular connection, a valve in said fuel supply pipe whereby the flow of oil therethrough may be regulated, a check valve in said tubular connection between said fuel-oil supply pipe and said fuel-chamber, a tubular connection between the other end of
40 said cylinder and said air intake ports, a crank-shaft, a fly-wheel on said shaft, pistons in said cylinder adapted to cover and uncover said ports, trunnion pins secured in
45 said pistons and extending outwardly through said slots, levers pivoted on said trunnion pins, means to support the upper ends of said levers, and pitmen pivoted on the cranks in said crank-shaft, and to said levers, substantially as set forth.

In testimony whereof I affix my signature, in presence of two witnesses.

EDWARD J. HARRINGTON.
